MANUFACTURE AND PRODUCTION OF
STAPLE FIBER

Frederick Roberts Coleshill, Holywell, Wales, and
John Hunter McKeown, Leamington Spa, England, assignors to Courtaulds Limited, London, England, a company of Great Britain

Application January 4, 1938, Serial No. 183,392
In Great Britain January 8, 1937

5 Claims. (Cl. 19-1)

This invention relates to the production of artificial threads, filaments and the like in the form of staple fiber.

It has already been proposed, in the production of staple fiber, to stretch the thread immediately after formation on its way to the cutting device. For example, it has been proposed in the production of staple fiber from viscose to collect the threads leaving the setting bath so that they form a bundle or tow and pass this bundle successively around two driven rollers of which the second has a greater peripheral speed than the first and then to lead the bundle to a cutting device of the type described in British specification No. 289,028 convention date April 20, 1927, in which the bundle is caused by centrifugal force to pass along a radial passage in a rapidly rotating disc at the periphery of which is stationed a cutting blade, which at each revolution cuts off the portion of the bundle which has emerged from the radial passage. It has also been proposed, during the stretching process, to subject the bundle of threads to treatment with hot water or hot dilute acid.

When a thread or a bundle of threads is subjected to considerable stretching a certain amount of contraction of the thread takes place as it leaves the stretching device and if the thread be led directly therefrom to a cutting device the contraction takes place in jerks, so that the staple length of the cut threads is not uniform.

The object of the present invention is to provide an improvement in the process of producing staple fiber from artificial threads, filaments and the like which have been stretched, whereby a more uniform length of staple is obtained.

According to the present invention, in the production of staple fiber by a process in which a continuous thread, filament or the like, or bundle thereof, is stretched by passing it in succession round two or more peripheral surfaces each rotating with a peripheral speed greater than the previous one and is thereafter cut, we obtain a more uniform length of staple by including the step of passing the aforesaid thread or bundle of threads after it has passed round the stretching device, but before it arrives at the cutting device, round another peripheral surface rotating with a peripheral speed so much less than that of the last of the stretching surfaces as to compensate approximately for the contraction of the thread which takes place.

For example, the thread may be stretched by passing it in succession round two rollers, the peripheral speed of the second of which is

greater than that of the first. After it leaves the second roller it is then passed round a third roller rotating at a somewhat slower peripheral speed than the second roller before it reaches the cutting device. This third roller may be driven by a shaft separate from that bearing the second roller or it may be on the same shaft, or it may form a part of the second roller with reduced diameter.

The peripheral speed of the third roller is less than that of the second roller by so much that the contraction of the thread leaving the second roller is approximately compensated for. The thread is then neither slack nor tight on the third roller and is in the most suitable condition for forwarding direct to the cutting device for the production of staple fibers of more uniform length.

In another example, the thread or bundle of threads may be stretched by passing several times round a conical roller, arriving at the narrow end and being caused to move in a helical path towards the broad end. Owing to the difference in the peripheral speeds at the narrow and the broad end, stretch will take place as the thread is moved along the roller. The improved step of the invention is thereupon effected by passing the thread several times round a second conical roller, which may be integrally united and placed base to base with the former one, in such a manner that it passes helically along the roller from the broad to the narrow end. In this case the diameter and therefore the peripheral speed of the narrow end of the second roller is just sufficiently less than the diameter and peripheral speed of the broad end that the contraction of the thread is approximately compensated for.

Any one or more of the peripheral surfaces referred to above may be grooved, corrugated or fluted if desired.

The drawing illustrates by way of example only apparatus for carrying out the process of the present invention.

Figure 1 shows in elevation individual threads 1 passing through a guide 2 to form a tow or rope of threads 3. The tow 3 is stretched by passing it in succession round rollers of equal diameter 4 and 5, 5 rotating faster than 4. After leaving the roller 5 the tow is passed round another roller 6 the same size as 4 and 5, but rotating at a speed so much slower than 5 that a contraction of the thread on leaving 5 is compensated for. After leaving the roller 6 the tow is passed over the guide 7 to the hopper 8 of a

cutter 9 of the type described in British specification No. 289,028.

Figures 2 and 3 show in elevation and plan respectively, an arrangement wherein the tow 5 is passed round the roller 4 then round a roller 5 of equal diameter between which stretching takes place, since 5 is rotating faster than 4. The tow is then passed via a guide 10, round the part 6 of roller 5 of reduced diameter and then 10 as in Figure 1.

Figure 4 shows in plan, stretching the tow 3 by passing it several times round a conical roller 11, along which it is caused to move from the narrow to the broad end by means of a rod 13 inclined at an angle to the axis of the conical roller. After arriving at the broad end of the conical roller 11 the tow is allowed to contract by passing along a conical roller 12 from the broad end to the narrow end and is then passed 20 to the cutter. The conical rollers 11 and 12 are united end to end.

What we claim is:

1. In the manufacture and production of staple fiber by a process in which a continuous thread 25 or bundle of threads is stretched by passing it in succession round two or more peripheral surfaces each rotating with a peripheral speed greater than the previous one and is thereafter cut, the step of passing the said thread or bundle after it has passed round the aforesaid surfaces, but before it arrives at the cutter, round another peripheral surface rotating with a peripheral speed so much less than that of the last of the stretching surfaces as to compensate 35 approximately for the contraction of the thread which takes place, and thereafter immediately cutting said thread or bundle while in said contracted state, the passage of said thread or bundle round all of said peripheral surfaces and 40 to said cutting step being continuous.

2. In the manufacture and production of staple fiber by a process in which a continuous thread or bundle of threads is stretched by passing it in succession round two rollers, the second 45 of which is rotating at a greater peripheral speed than the first and is thereafter cut, the step of passing the said thread or bundle, after it has passed round the aforesaid rollers and before it arrives at the cutter, round a third roller 50 rotating with a peripheral speed less than that of the second roller, and thereafter cutting said thread or bundle without any interruption in the continuous passage thereof over said rollers and to said cutting step.

55 3. In the manufacture and production of sta-

ple fiber by a process in which a continuous thread or bundle of threads is stretched by passing it in succession round two rollers, the second of which is rotating at a greater peripheral speed than the first and is thereafter cut, the step of 5 passing the said thread or bundle before it arrives at the cutter round part of the second roller with a reduced diameter, and thereafter cutting said thread or bundle without any interruption in the continuous passage thereof over said rollers and to said cutting step.

4. In the manufacture and production of staple fiber by a process in which a continuous thread or bundle of threads is stretched by passing it in succession round at least two peripheral 15 surfaces each rotating with a peripheral speed greater than the previous one and is thereafter cut and in which contraction of the thread takes place as it leaves the stretching device and if the thread be led directly therefrom to a cutting device the contraction takes place in jerks so that the staple length of the cut threads is not uniform, the step of improving the uniformity of the staple length which comprises passing the said thread or bundle after it has passed round the aforesaid surfaces but before it arrives at 20 the cutter round another peripheral surface rotating with a peripheral speed so much less than that of the last of the stretching surfaces as to compensate substantially for the said contraction and thereby avoid said jerks and attendant non-uniform staple length, and thereafter immediately cutting said thread or bundle while in 25 said contracted state, the passage of said thread or bundle round all of said peripheral surfaces and to said cutting step being continuous.

5. Process for the manufacture and production of staple fiber of substantially uniform length, which comprises stretching a continuous thread or bundle of threads by passing it in succession 40 round at least two peripheral surfaces each rotating with a peripheral speed greater than the previous one, subsequently passing the thread round another peripheral surface rotating with a peripheral speed so much less than that of the 45 last of the stretching surfaces as to compensate approximately for the contraction of the thread which takes place, and passing said threads to a cutter while in said compensated condition, the passage of said thread or bundle being continuous through said stretching and compensating steps to said cutter.

FREDERICK ROBERTS COLESHILL,
JOHN HUNTER McKEOWN.
